UNITED STATES PATENT OFFICE.

CHARLES B. BREWER, OF COLLEGE PARK, MARYLAND.

RECORD AND PERCENTAGE CHART FOR BASEBALL AND OTHER GAMES.

Application filed July 26, 1921. Serial No. 487,647.

To all whom it may concern:

Be it known that I, CHARLES B. BREWER, a citizen of the United States, residing at College Park, in the county of Prince Georges and State of Maryland, have invented certain new and useful Improvements in Record and Percentage Charts for Baseball and Other Games, of which the following is a specification, reference being had 10 therein to the accompanying drawing.

This invention relates to record and percentage charts for baseball and other games, and particularly to charts for recording the results of games during a ball season.

15 The object of the invention is to provide a chart of such simple form that it may readily be understood.

Another object of the invention is to present a chart so constituted that it may readily be changed from time to time as the particular game charted progresses.

20 The chart characterized by my invention provides for several features, among others of which may be mentioned the following:

25 1. A record of any succession of games—for example, between different clubs in any of the existing baseball leagues, or between contestants thereof—may thereby be kept which will show whether, at any particular time, preceding and successive games have 30 been won or lost.

2. The general path or curve by which a position of the contestant has been attained relatively to another contestant may thus 35 be recorded.

3. The relative positions, as regards percentages of games won—whether the number played by each contestant is the same number as or a different number from another 40 or others—may thus be charted.

4. Tabulated data, in one column, giving for each particular game won: the date played, the score, and from what team won.

5. Tabulated data, in another column, 45 giving for each particular game lost: the date played, the score, and to what team lost.

6. Character markings to show with whom and when tie games are played; games not 50 scheduled to be played or not played because of rain or other reason; "double header" games; and whether games are played on the home grounds or abroad; and other data desired to be recorded about particular 55 games or days.

7. The variation in percentage-value of

a game won, or a game lost, and full information as to date played, with whom, resulting score, etc., may thus be laid off and readily understood.

8. Comparative readings of the performances, such as complete victories, for points of excellence—for instance, the batting averages, etc.—of two or more teams on the same chart.

60 In the accompanying drawings, I have illustrated two preferred forms of charts, though these are in the nature of examples, and it is to be understood that the same may be varied according to the particular use 65 for which the chart is to be utilized.

In these drawings:

Figure 1 is a plan view of the chart for plotting the record of one particular ball team; and

75 Fig. 2 is a plan view of the chart for plotting the record and comparative standings of two or more teams, two teams being shown.

Referring to these drawings, it is to be 80 understood that the games plotted on the vertical lines *a* are those which have been won; whereas those which have been lost are plotted on the horizontal lines *b*.

Each space *c* formed between the vertical 85 and horizontal lines represents, say, a game.

The vertical lines are arranged in groups of ten and, similarly, are the horizontal lines.

The converging lines *d* will represent the 90 percentages of, say, victories of the total games played. The spacing of these lines *d* is nowhere equidistant, except on lines drawn at an angle of 45° to the vertical. For each 100%, a heavy line is, by preference, drawn, and the intermediate lines are lighter, and each represents 10%.

95 It will be understood that as a particular club increases the number of games won, the percentage rises and the lines *d*, intersecting the lines *b*, indicate the exact percentage.

100 The following explanation will suffice, it is thought, to exemplify the use of the chart:

105 Referring to Fig. 1 of the drawings, it will be seen from the chart that, up to May 28th, the team of which the record is being kept lost twenty games and won eighteen. The percentage of victories can thus be 110 read as 474%.

It will also be seen from the upper col-

- 2
- wins of designating matter that the game which brought the team to the 474% point on that date was lost to team "Dt", designating Detroit, by a score of 2 to 3, and the 5 underscoring under the letters "Dt" indicates that the game was played at the home grounds of the "Dt" team, namely, Detroit, instead of at the grounds of the team being plotted.
- 10 A study of the chart will show that the team of which the record is being kept won the last five games plotted, thereby increasing its percentage from 510% to 530%.
- 15 The chart accounts for the date and the inactivity or break in the schedule of the team, as well as indicating the played games. Thus, between April 17th and April 19th, the diagonal line shows that a game was not played on account of rain, or in travel 20 to another city, or for any other reason. Similarly, between the dates of May 3rd and May 6th, there were two games omitted by reason of rain, travel, etc., as indicated by the two short diagonal lines. Whether 25 this was on account of rain or travel may be indicated, for instance, by placing a small "r" at the end of the diagonal line representing a game not played on account of rain, and a small "t" at the end of the diagonal line to indicate a game not played on account of travel, etc.
- 30 The chart also indicates, by the small circles designated *e* and *f*, that, on May 8th a tie game was played in addition to the 35 5—4 game and that another tie game was played between May 25th and May 27th. Ordinarily, a tie game will be indicated by making the small circle through the line indicating one of two games played on the 40 same day, as at *e*; but where the tie game happens to be the only game of the series with a contesting team played on a particular day, the tie game may be indicated by placing the circle at the corner of the block at the end of the line indicating the last game 45 played with the preceding team prior to the tie game.
- 50 The chart also provides for indicating, by double parallel lines—instead of the usual heavy single line marking the path of the team—a "double header," as noted at *g* for the game played on May 30th. The columns at the side and top also show this when checked; but the double line designation is added to make a reading of the past performances of a team by the plotting lines more simple than by having to resort to the designating data in the side and top 55 columns.
- 60 Referring to Fig. 2 of the drawings, it will be seen that the chart therein disclosed illustrates the adaptability of my invention to recording the performances or results of games played by two or more teams on the 65 same card. By this arrangement, all the information for each team, as noted for the team shown in Fig. 1, is given and, in addition, this form of chart affords a more ready means of illustrating the comparative performances of any two teams where peculiar rivalry between them for standing in the league may exist, such, for example, as the pennant race of the two leading teams of a league. As illustrated by Fig. 2, the record of past performances and present standing of two teams, designated, here, New York and Cleveland, are entered. As shown, the record of the New York team is indicated by the solid line, while the record of the Cleveland team is indicated by the dotted line. As in the example shown in Fig. 1, games won are plotted on the vertical lines and games lost on the horizontal lines. The diagonal lines register the percentage of games won and each game won moves the end of the line toward the higher percentage. Similarly, each game lost moves the end of the line towards the lower percentage.
- 70 The tables at the side and top of the chart show the dates on which the games are played and are written in the same parallel space wherein the game is plotted, the tables at the side showing the games won and those at the top showing the games lost. All dates are accounted for to prevent error in plotting days on which games are not played on account of rain or for other reason, and are shown by the short diagonal lines, the solid diagonals marking such reason for the New York team, and the dotted diagonals those of the Cleveland team.
- 75 In keeping a comparative record of the performances of two teams, as contemplated by the example shown in Fig. 2, it will be understood that the two teams may not play games on the same dates, so that there will be a difference in the points of entry of dates in the parallel columns of the total number of games played up to a given date; but the percentage standing of each team will be accurate.
- 80 It is to be understood that the chart devised by me may be used for keeping a record of the performances of any number of teams, on the same card, by merely placing additional designating columns on the side and top of the chart for entering 85 the names of the other teams, the course of the games, etc.; and that other plotted performances may be indicated by using solid, dotted, and dot-and-dash lines, or by using ink or pencils of different colors for 90 the several teams.
- 95 It is also to be understood that the chart may be used for the purpose of recording the batting, fielding, base-running, and error averages of a ball team, in the same manner 100 and on the same chart that the standing of

the team may be plotted; that is, the percentages will be calculated in the same way, either singly or all together, by using different colored pencils or ink, etc., in making 5 the plotting lines or curves.

What I claim is:

1. A chart comprising a body bearing approximately equally spaced horizontally and vertically arranged lines disposed at approximately right angles to each other to define intersecting columns for the reception of data relating to games won and games lost, respectively, and a plurality of lines radiating from one corner and extending 10 toward opposite edges of the chart, whereby points of intersection of said radiating lines with said horizontally and vertically arranged lines indicate percentages of games won and lost.
2. A chart comprising a base bearing delineations thereon including horizontally and vertically arranged lines constituting columns for the reception of data relating to games won and games lost, respectively, 15 said lines being arranged in groups of predetermined number; certain of said lines bearing numbers corresponding to the number of lines computed from a predetermined point and indicating that number of games 20 won; certain other lines bearing numbers corresponding to the number of the line computed from a predetermined point and indicating that number of games lost; and a plurality of radial lines extending from one 25 corner of the chart toward the opposite edges thereof and bearing delineations indicating percentages.
3. A chart comprising a base bearing delineations thereon including horizontally and vertically arranged lines constituting columns for the reception of data relating to 30
- 40

games won and games lost, respectively; said lines being arranged in groups of predetermined number; certain of said lines bearing numbers corresponding to the number of lines 45 computed from a predetermined point and indicating that number of games won; certain other lines bearing numbers corresponding to the number of the line 50 computed from a predetermined point and indicating that number of games lost; a plurality of radial lines extending from one corner of the chart toward the opposite edges thereof and bearing delineations indicating percentages; said lines constituting 55 a body-portion of the chart; and a plurality of lines extending outwardly beyond the body-portion and constituting columns for the reception of data relating to the names of teams, the dates of games, and the score. 60

4. A game chart comprising a body bearing approximately equally spaced horizontally and vertically arranged lines disposed at approximately right angles to each other to define intersecting columns for the reception of data relating to games won and lost, respectively, 65 a plurality of lines radiating from one corner and extending toward opposite edges of the chart, whereby points of intersection of said radiating lines with said 70 horizontal and vertical lines indicate percentages of games won and lost, markings on the chart following the direction of certain of said horizontal and vertical lines between intersections thereof to indicate performance of teams on certain days, double markings to indicate double performance on a single day, and other markings at intersections of said horizontal and vertical lines 75 to indicate lack of performance. 80

In testimony whereof I affix my signature.
CHARLES B. BREWER.
